PHONOGRAPH RECORD RACK

David Vernik, 845 Tyson Ave., Philadelphia, Pa.

Filed Sept. 15, 1961, Ser. No. 66,728

Term of patent 14 years

(Cl. D33—3)

FIG. 1

FIG.4

FIG. 3

FIG. 5

FIG. 1 is a perspective view of a design for a phonograph record rack, showing my new design;

FIG. 2 is an enlarged fragmentary perspective view of one of the phonograph record album holding tiers of FIG. 1;

FIG. 3 is a fragmentary perspective view of the rack on an enlarged scale, the dotted line showings of record albums being for illustrative purposes only;

FIG. 4 is an enlarged top plan view of the fragmentary rack of FIG. 2; and

FIG. 5 is a bottom plan view thereof.

I claim:

The ornamental design for a phonograph record rack, substantially as shown and described.
